United States Patent Office

Des. 192,886
Patented May 22, 1962

192,886

JUG

Theodore Kaplan, 21 Ivanhoe St., Newton, Mass.

Filed Feb. 9, 1961, Ser. No. 63,876

Term of patent 14 years

(Cl. D58—5)

FIG. 2

FIG. 1

FIG. 3

FIG. 1 is a side elevational view of a jug showing my new design, a portion thereof being shown broken away for purposes of illustration.

FIG. 2 is a top view thereof.

FIG. 3 is a rear elevational view thereof.

I claim:

The ornamental design for a jug, as shown.
